UNITED STATES PATENT OFFICE.

FREDERICK A. NIEMANN, OF CHICAGO, ILLINOIS, ASSIGNOR TO NIEMANN AND COMPANY, OF CHICAGO, ILLINOIS, A CORPORATION OF ILLINOIS.

CHANGE-MAKING MACHINE.

1,222,659.

Specification of Letters Patent. Patented Apr. 17, 1917.

Application filed November 9, 1914. Serial No. 371,188.

To all whom it may concern:

Be it known that I, FREDERICK A. NIEMANN, a citizen of the United States, residing at Chicago, in the county of Cook and State of Illinois, have invented certain new and useful Improvements in Change-Making Machines, of which the following is a specification.

My invention relates to a machine for making change, and particularly to machines suitable for use in situations where the amount of the purchase is a fixed unit, or a multiple thereof, as is the case at theaters selling seats at a uniform price, or with street railroads charging the passengers a constant fare per ride; the fixed unit representing, of course, a single ticket, admission or fare, and the multiple thereof the purchase of a number of tickets, admissions or fares, in one transaction. My invention contemplates a machine which will deliver the exact amount of change for any transaction, determined, in each case, first, upon the amount tendered by the purchaser, and second, by the number of unit values of his purchase, by the manipulation, for each transaction, of a single operating member, the several operating members bearing designations or being arranged so that the operator may readily select the appropriate one. While a machine constructed on this principle has a limited utility, since it does not possess the capacity which ordinary change makers have of subtracting any purchase amount from any amount tendered and delivering the right change, within its own field my machine has the very considerable advantage of simplicity both in construction and in operation. In the matter of construction it is cheaper to manufacture and smaller in size than the ordinary change making machines, and is much more durable and less likely to get out of order. So far as operation is concerned, it may be manipulated much more rapidly and certainly. The mental factor in the operation is simplified in the last degree, with the result that a mistake is practically impossible.

My invention has for its principal object to provide a change making machine having the above stated characteristics and capabilities.

The invention has for further objects to

provide certain novel features of construction suitable particularly for a machine operating upon this principle but susceptible, no doubt, of use in connection with change making machines of a different type.

The invention is illustrated, in a preferred embodiment, in the accompanying drawings in which—

Figure 1 is a front elevation of a change making machine designed for a purchase value unit of ten cents and multiples of the same up to four.

Fig. 2 is a plan view of this machine.

Figs. 3, 4 and 5, views, in perspective, of three different types of coin ejecting slides employed in the machine;

Fig. 6, a sectional view taken on line 6—6 of Fig. 1;

Fig. 7, a fragmental sectional view on line 7—7 of Fig. 1;

Fig. 8, a view, in perspective, of the base of the machine, and

Fig. 9, a similar view of the trough which receives the coins when ejected from the coin receptacles.

Like characters of reference designate like parts in the several figures of the drawings.

Referring to the drawings, 10 is a base plate supported by and preferably formed integrally with end wall members 11 and a back wall member 12, a space 13 intervening between the rear edge of the base and the back wall member 12. Arranged on the structure 10, 11, 12, is a casting 14 so as to provide a plurality of coin receptacles designated A to L inclusive, respectively, of suitable diameter for coins of different denomination, and preferably open in front so that the coin stacks within the same are visible to the operator. The coin receptacles are substantially upright, so that the coins feed down by gravity, but may have a slight slant.

The base is formed with a plurality of sets of parallel grooves, one set for each coin receptacle, the grooves extending from the front edge of the base to the rear edge. Each set is preferably made up of three grooves 15, 16 and 17. At the inner end of certain sets of grooves a recess 18 is provided directly under the corresponding coin receptacle; these recesses varying in depth according to the thickness of the coins which

they are intended to receive and according to the number of coins which are ejected at one operation.

The coins are ejected from the coin receptacles or rather, strictly speaking, from the recesses 18 in the base plate under the coin receptacles, by means of coin ejecting slides designated *a* to *l* respectively, in correspondence with the lettering of the coin receptacles. Each slide is provided with an operating member or finger piece 19 preferably bearing a numeral indicating (except in the case of slide *a*, as will be hereinafter explained) the denomination of the coin tendered by the purchaser for which change is to be returned. In a machine designed for purchase value units of ten cents these slides are of four different types (Figs. 3 to 5 inclusive). The construction of the slides designated *d*, *g*, *j* and *l* being the same as that of slides *b*, *e*, *i* and *k*, except that the parts are reversed.

The receptacle A contains a stack of five cent pieces. The slide *a* ejects these five cent pieces singly from the receptacle. The receptacle B also contains five cent pieces which are ejected three at a time by slide *b*. The receptacle C contains quarter of a dollar pieces which are ejected singly. The receptacle D contains half dollars ejected singly, the receptacle E five cent pieces ejected singly, the receptacle F quarters ejected singly, the receptacle G also quarters ejected two at a time, the receptacle H nickels ejected singly, the receptacle I dimes ejected two at a time, the receptacle J half dollars ejected one at a time, the receptacle K dimes ejected one at a time, and the receptacle L quarters ejected two at a time. The reason for providing for the ejection of quarters two at a time instead of halves one at a time is to balance the disbursement of these denominations as nearly as possible with the receipt of the same. With a ten cent purchase value the probabilities are that a much larger number of quarters will be received than halves. Hence the machine is designated to deliver quarters in places where, except for this reason, halves might just as well be delivered.

The further description of the construction of the parts of the machine had better be postponed until a brief statement of the operation is made. The operation is as follows:

The slides (except slide *a*), are divided into four groups, the slides *b*, *c* and *d* constituting the first group, designated by the numeral "1" on a subdivided area 20 of the front piece 21 of the machine, and are employed for making change as against a single purchase unit value, that is, to take a concrete case, where a single ticket is purchased. The second group of slides *e*, *f* and *g*, designated by the numeral "2" on the area 22,

make change when two tickets are purchased. The third group, designated "3" on the area 23, consisting of slides *h*, *i* and *j*, makes the change on the purchase of three tickets. Similarly, the fourth group, designated "4" on the area 24, consisting of slides *k* and *l*, make the change for a purchase of four tickets.

If the purchaser buying a single ten cent ticket tenders a quarter, the operator forces slide *b*, the finger piece of which is plainly marked "25". Three five cent pieces are ejected from coin receptacle B. If the purchaser tenders a half dollar the operator pushes slide *c*, which is marked "50", and ejects a twenty-five cent piece from the receptacle C. The slide *c* is formed with a lug 25 which engages a lug 26 on slide *b*. Therefore when slide *c* is manipulated slide *b* is moved with it and ejects three five cent pieces, making in all forty cents, the correct change for half a dollar. If the purchaser tenders one dollar slide *d*, which is marked "100", is manipulated, ejecting a half dollar from receptacle D. Slide *d* is formed with a lug 27 which engages a lug 28 on slide *c*. The manipulation of slide *d*, therefore, operates slides *c* and *b*, ejecting from receptacle C and B one quarter and three five cent pieces, making in all ninety cents, the correct change from one dollar.

If the purchaser buys two tickets and tenders a quarter the operator presses in slide *e* of the group marked "2", this slide bearing the indication "25". A five cent piece is ejected from receptacle E. Slides *e*, *f* and *g* correspond in construction to slides *b*, *c* and *d*, respectively so that if a fifty cent piece is tendered for two tickets the operator, by manipulating slide *f*, ejects thirty cents, a quarter from receptacle F and a nickel from receptacle E, and if a dollar is tendered the operator, by manipulating slide *g*, marked "100", ejects eighty cents, two quarters from receptacle G, one quarter from receptacle F, and a nickel from receptacle E.

If the purchaser buys three tickets and tenders thirty-five cents, a quarter and a ten cent piece, for example, the operator presses slide *h* which ejects a nickel from receptacle H. If the purchaser tenders fifty cents for the three tickets, slide *i* is manipulated to eject two dimes from receptacle I. There is no connection between slides *i* and *h* as the exact change can be made from the dime receptacle I. If the purchaser tenders a dollar, slide *j* is manipulated, this slide having a lug 27 engaging a lug 28 on slide *i*, with the result that seventy cents change is delivered, one half dollar from receptacle J and two dimes from receptacle I.

If the purchaser wishes four tickets and gives a half dollar, slide *k* is manipulated to eject one dime from receptacle K. If he

tenders a dollar, slide *l* is manipulated to deliver two quarters from receptacle L and one dime from receptacle K, the slides *l*, *k* having the same relation to each other as slides *j* and *i*.

It will be recognized that my invention is not limited to any particular purchase value unit or any particular number of multiples of such unit. The machine might 10 be designed for a five cent ticket or for any desired purchase value unit or series of multiple units. This would, of course, necessitate a different interrelation between the slides and a different division between the 15 slides into groups but not any change in the principles of construction and operation of the machine.

The receptacle A and its ejecting slide *a* constitute an additional device for making 20 change in the case of half units, for example, if half fares or half rate tickets are sold. If the purchaser wishes a single half ticket and tenders a dime the operator, by manipulation of slide *a*, ejects a nickel from 25 the receptacle A. If the purchaser tenders a quarter the operator presses in the quarter slide *b* of the "one ticket" group and also the half rate ticket slide *a* which gives twenty cents in change. Similar operations 30 are performed by means of slides *c* and *d* in connection with slide *a* in case the purchaser tenders fifty cents for a single ticket.

If the purchaser buys two tickets, one a full ten cent ticket and the other a five cent ticket, the operator presses in the appropriate slide of the "two ticket" group and also five cent ticket slide *a*. The operation is strictly analogous in case three or four 35 tickets are purchased, one of which is a half value ticket.

The coins, when ejected, fall into a trough 29 arranged directly under the space 13 at the back edge of the base 10, and are conducted into a cup 30 at the front side of the 40 machine within easy reach of the operator.

The slides *a*, *b* and *c*, etc., are preferably formed of sheet metal pressed so that they are provided with pairs of flanges 31, 32, 33, 34, and 35, 36. These flanges are guided 45 in the pairs of slots 15, 16 in the base. The intermediate slots 17 have springs 37 which are attached at one end to a rod 38 extending across the machine from side to side, and at the other to lugs 39 formed on the slides.

50 The flanges 31, 34, 36 are formed with teeth 40 constituting, in each case, racks adapted to be engaged by dogs 41 occupying enlargements 42 of one or other of the slots 15 or 16, as the case may be, the dogs being 55 notched at 43 and pivoted on a rod 44 against which they are pressed by springs 45. The dogs prevent the retraction of the slides until their forward movements have been completed. If some such device were 60 not employed the slide might be pushed half

way in and then released which would push the lower coins part-way out and allow the coins above these coins to tilt downwardly at their forward edges, preventing the further operation of the machine. When the 70 forward movement of any slide is completed a lug 46 at its forward end bears against a shoulder 47 on the dog, tilting the nose 48 of the dog out of contact with the rack, the spring 45 assuming a position at the other side of the pivotal point 44. When the slide is fully retracted a hook 49 on the inner end of the slide engages with the nose 48 on the dog so as to tilt the dog back to its normal 75 engaging position.

The coin receptacles are preferably open 80 in front so that the operator can keep watch of the supply of coins therein and replenish the same when necessary. In order to prevent the possibility of the machine delivering short change the coin receptacles from 85 which two or more coins are delivered at one operation, and the receptacles, the slides of which have interengaging relationship, may be provided, in each case, with a follower 50 (Fig. 6) having a handle 51 projecting through the opening in the receptacle at the front. If, as shown in Fig. 6, three coins are intended to be delivered from 90 the receptacle at one operation, and there are only two coins in the receptacle, or if 95 there be but one, the follower, by assuming the dotted position, will prevent the manipulation of the slide ejecting coins from this receptacle. If followers of this sort are used 100 in receptacles, the slides of which are engaged one by the other, the followers will operate similarly to prevent the manipulation of the selected slide if any of the coin receptacles corresponding with the interrelated slides have become emptied or contain 105 a less number of coins than are intended to be ejected at one operation.

While I have described my invention as embodied in certain preferred arrangements, 110 it will be understood that modifications might be devised without departure from the principles of the invention. Therefore, I do not wish to be understood as limiting the invention to the particular arrangements, 115 constructions and devices shown and described except so far as the claims distinctly specify such limiting features.

I claim:

1. In a change making machine, the combination with a plurality of receptacles for coins, of a plurality of channel-shaped slides provided with racks and adapted to be manipulated beneath said receptacles so as to eject coins therefrom, and means adapted to 120 engage said racks to prevent the retraction of said slides until the forward movement of said slides has been completed.

2. In a change making machine, the combination with a base member formed with 125

- parallel slots terminating in coin recesses, of coin receptacles arranged above said recesses, a plurality of channel-shaped coin-ejecting slides provided with a rack on one 5 of their flanges and operating in said slots so as to eject the coin retained in said recesses, springs to retract said slides to their normal position, and means for preventing the retraction of said slides until the forward 10 movements of the same have been completed, comprising a pivoted pawl arranged in one of said slots adapted to engage said rack during said forward movement.
- 15 3. In a change making machine, the combination with a base formed with a pair of parallel slots, of a substantially upright coin receptacle arranged at one extremity of the slots, a coin ejecting slide having flanges 20 projecting into said slots, the end of which slide engages and ejects a coin from the lower end of the coin stack in said receptacle.
4. In a change making machine, the combination with a base formed with a pair of parallel slots, of a substantially upright coin receptacle arranged at one extremity of the slots, a coin ejecting slide having flanges projecting into said slots, the end of which 25 slide engages and ejects a coin from the lower end of the coin stack in said receptacle, one of said flanges being formed with a rack, a dog adapted to engage said rack on the forward stroke of the slide, and means on the slide which moves the dog out of operative engagement with the rack when the slide has completed its forward stroke.
5. In a change making machine, the combination with a base formed with a pair of parallel slots, of a substantially upright coin receptacle arranged at one extremity of the slots, a coin ejecting slide having flanges projecting into said slots, the end of which slide engages and ejects a coin from the lower end of the coin stack in said receptacle, one of said flanges being formed with a rack, a dog adapted to engage said rack on the forward stroke of the slide, and means on the slide which moves the dog out 30 of operative engagement with the rack when the slide has completed its forward stroke.
- 5 of their flanges and operating in said slots so as to eject the coin retained in said recesses, springs to retract said slides to their normal position, and means for preventing the retraction of said slides until the forward 10 movements of the same have been completed, comprising a pivoted pawl arranged in one of said slots adapted to engage said rack during said forward movement.
- 15 3. In a change making machine, the combination with a base formed with a pair of parallel slots, of a substantially upright coin receptacle arranged at one extremity of the slots, a coin ejecting slide having flanges 20 projecting into said slots, the end of which slide engages and ejects a coin from the lower end of the coin stack in said receptacle.
4. In a change making machine, the combination with a base formed with a pair of parallel slots, of a substantially upright coin receptacle arranged at one extremity of the slots, a coin ejecting slide having flanges projecting into said slots, the end of which 25 slide engages and ejects a coin from the lower end of the coin stack in said receptacle, one of said flanges being formed with a rack, a dog adapted to engage said rack on the forward stroke of the slide, and means on the slide which moves the dog out of operative engagement with the rack when the slide has completed its forward stroke.
5. In a change making machine, the combination with a base formed with a pair of parallel slots, of a substantially upright coin receptacle arranged at one extremity of the slots, a coin ejecting slide having flanges projecting into said slots, the end of which slide engages and ejects a coin from the lower end of the coin stack in said receptacle, one of said flanges being formed with a rack, a dog adapted to engage said rack on the forward stroke of the slide, and means on the slide which moves the dog out 30 of operative engagement with the rack when the slide has completed its forward stroke.
- of operative engagement with the rack when the slide has completed its forward stroke and into engagement therewith on the complete retraction of the slide.
6. In a change making machine, the combination with a base formed with three parallel slots, of a substantially upright coin receptacle at one extremity of the slots, a coin ejecting slide having flanges projecting into two of said slots the end of which slide engages and ejects a coin from the lower end of the coin stack in said receptacle, and a spring engaged at one end with said base and at the other with said slide which lies in the third slot.
7. In a change making machine, the combination with a base formed with a pair of parallel slots terminating at one end in a coin recess, of a substantially upright receptacle arranged over said recess, and a coin ejecting slide having flanges projecting into said slots, the end of which slide engages and ejects a coin from said recess.
8. A coin ejecting slide for change making machines comprising a channel-shaped sheet metal element provided with a finger piece.
9. In a change making machine, the combination with a coin ejecting slide comprising a channel-shaped sheet metal element provided with a finger piece and formed with a rack on one of its flanges of a spring-actuated pivot member adapted to engage said rack.
10. In a change making machine, the combination with a base formed with a plurality of parallel slots, of a plurality of coin receptacles positioned over said base, and coin ejecting slides formed with flanges which extend into said slots so as to guide the movement of the slides, said slides being formed with laterally extending, co-engaging lugs whereby the manipulation of certain of the slides produces operative movements in others of the same.
